UNITED STATES PATENT OFFICE.

WILLARD A. SLOPER, OF INDEPENDENCE, OREGON.

CROSSCUT-SAW TOOL.

1,369,565.

Specification of Letters Patent. Patented Feb. 22, 1921.

Application filed October 25, 1919. Serial No. 333,234.

To all whom it may concern:

Be it known that I, WILLARD A. SLOPER, a citizen of the United States, residing at Independence, in the county of Polk and State 5 of Oregon, have invented new and useful Improvements in Crosscut-Saw Tools, of which the following is a specification.

This invention relates to tools for working upon cross cut saws for placing them in 10 proper condition, and comprises a single tool which is a combination of all the tools required to properly dress a cross cut saw, including a jointer, raker tooth jointer, raker tooth swaging gage, side file, set 15 block, and set gage, arranged to afford the greatest convenience to the saw filer.

An important object is the provision of a device of this character which is provided with a clamping member so arranged that 20 the file may be securely engaged with the device in a selected position whereby the points of the saw teeth may be filed or whereby the sides may be filed, the device having upon its sides ribs and the ribs on 25 one side, the side upon which the file is disposable, serving as a guide whereby the file may be properly positioned for side filing, adjusting screws being provided for shifting the position of the file toward and away 30 from the outermost edge of the guide rib.

Another object is the provision of a device of this character which will be simple and inexpensive in manufacture, which may be readily used by those understanding the 35 art, and which will be very efficient and labor saving in use, and a general improvement in the art.

With the above and other objects and advantages in view, the invention consists in 40 the details of construction to be hereinafter more fully described and claimed, and illustrated in the accompanying drawings in which—

Figure 1 is an edge elevation showing the 45 device in use as a saw set,

Fig. 2 is a side elevation thereof, the saw being shown in section,

Fig. 3 is a view similar to Fig. 2, showing the device in position for use as a set gage,

Fig. 4 is a side elevation showing a file 50 engaged thereon and in position for jointing the saw,

Fig. 5 is an elevation of the device, showing the same in use for jointing the raker

55 teeth,

Fig. 6 is an elevation of the device show-

ing it used as a gage for the raker teeth, after being properly dressed and swaged,

Fig. 7 is an elevation of the device having a file secured thereon in position for side 60 filing,

Fig. 8 is a cross sectional view on the line 8—8 of Fig. 7,

Fig. 9 is a cross sectional view on the line 9—9 of Fig. 4, and

Fig. 10 is a detail sectional view, showing the means for adjusting the raker tooth jointer gage plate.

Referring more particularly to the drawings, the numeral 15 designates the body of 70 the device which is formed elongated in shape and which is provided at its center with longitudinally extending ribs 16 and which is provided upon one edge with flanges 17 having the same degree of extension beyond the body as the ribs 16. On each side of the central ribs the body is cut away, as shown at 18 and 19, to reduce the weight of the device and also to afford finger engaging means. One edge of the body 80 has threaded therethrough a screw 20 which has its head extending within the cut away portion 19 so that the head may be grasped and turned for adjusting the screw. Threaded transversely through the body between the central ribs and the other edge 85 are screws 21, as shown.

This other edge of the body is recessed at substantially its center, as shown at 22, and within this recess is disposed a hardened 90 steel plate 23 which is provided with a slot 24 and which is held in adjusted position with respect to the bottom of the recess by screws 25 and 26, the former of which pass only into the body and have their heads disposed beneath holes 27 formed in the plate 23 and the latter of which passes through the plate 23 and into the body. By loosening the center screw 26 and then inserting a screw driver through the holes 27, the end 100 screws 25 may be screwed out for moving the plate 23 away from the bottom of the recess, for a purpose to be hereinafter explained.

Extending from one end of the recess 22 to the adjacent end, the body is provided on 105 both sides with overhanging flanges 28. Formed upon or secured upon the edge of the body and extending from the other end of the recess 22 to the other end of the body is a set block 29 which has a hardened outer 110 face and which has its edge adjacent the end of the recess beveled, as shown at 30. The

sides of this set block toward the body are also formed as plane surfaces, as is also the side of the flange 28 on the side from which extends the plate 23.

5 Threaded into the edge of the body adjacent the recess 22 is a gage pin 31 which is adapted to coöperate with the outer hardened face of the set block 29 for gaging the proper set to a saw tooth, as will be hereinafter explained.

10 Extending transversely through the guide portion of the set block 29 is a clamping member 32 which has one end threaded and provided with an adjusting nut 33. The other 15 end of this member 32 is reflexly bent, as shown, to provide a retaining lug 34 which is beveled upon both sides, as shown at 35 and 36.

15 In the operation of the device, referring to Figs. 1 and 2, it will be seen that it is arranged for use in setting the teeth. When the device is to be used for this purpose it is positioned with the hardened face of the set block 29 against the saw, as clearly shown 20 in Figs. 1 and 2, with the point of the teeth disposed at the beveled surface 30. The operator then grasps a hammer and strikes a smart blow upon the tooth and bends it onto the beveled surface 30. After the tooth 25 has been thus set and it is desired to ascertain whether or not the setting is uniform and proper, the device is moved into the position shown in Fig. 3, that is the hardened face of the set block 29 is disposed against 30 the saw at a point farther away from the tooth to bring the gage pin 31 in such position that it will contact with the point of a tooth. When the tooth is properly set the angularly bent point should just touch the 35 end of the gage pin 31 while the saw is disposed perfectly flat against the hardened outer face of the set block. If a tooth is found to have an insufficient set, the device is moved to the position shown in Figs. 1 and 2 40 and the tooth again struck with the hammer to bend it still more. If a tooth is found to have too much set the point instead of contacting with the point of the gage pin 31 will strike against the side thereof. In such an 45 event the device is so moved that the tooth will be disposed against the plane hardened face of the set block 29, after which the operator strikes a blow upon the tooth with a hammer to flatten the tooth slightly. This 50 operation is continued until the teeth are uniformly and properly set. It will be observed that the gage pin 31 is adjustable and held by a nut lock.

55 In jointing a saw, that is filing down the points of the teeth so that they will all lie in the same plane, use is made of a file designated by the letter B and this file is arranged as shown in Figs. 4 and 9, that is the file is laid with one flat side engaging beneath the 60 planed underside of the set block at one side

of the body, this flat side of the file also engaging against the flange 28 on the edge of the body at the same side thereof. It is understood that the clamping nut 33 is first loosened so that the clamping member 32 70 may be engaged upon the outer edge of the file, the lug 34 engaging against the other flat side of the file. The nut 33 is then tightened and owing to the beveled edge 35 of the lug 34, the file will be securely clamped upon 75 the body. The operator then grasps the device in his hand and places it with the body against one side of the saw A and with the file disposed upon the points of the teeth, as clearly shown in Fig. 4. He then reciprocates the device and the file as one and in that way files down any teeth which might be of excessive length, until eventually all the teeth are of the same length.

80 When the device is to be used for jointing or dressing the raker teeth, the file is removed from in engagement with the body and the device is so positioned that a raker tooth extends through the slot 24 in the plate 23 with the body disposed against the side of the saw. 90 The operator then grasps the file in one hand and properly dresses the raker teeth. As previously stated, the plate 23 is adjustable toward and from the bottom of the recess 22 within which it is disposed so that the degree of extension of the raker tooth beyond the outer face of the plate 23 may be regulated, it being understood that when the device is used for jointing a raker tooth the adjacent teeth are disposed against the 95 planed underside of the set block 29 and the underside of the flange 28 at the side of the body from which the plate 23 projects.

100 After a raker tooth has been thus jointed or dressed and it is desired to ascertain whether or not the raker tooth is of the proper length, which should be a trifle less than that of the cutting teeth, the device is disposed in the position shown in Fig. 6, that is it is placed with the edge opposite 105 the setting block flat upon the points of the teeth at both sides of the raker tooth to be tested. The screw 20 is adjusted so that it will project beyond the edge of the body an extent equal to the proper distance between the length of a cutting tooth and a raker tooth. If the raker tooth has been properly dressed the point of the screw 20 will just contact with either point of the raker tooth. If the screw does not contact properly with the points of the raker tooth it is obvious that the raker tooth needs further dressing, in which event the previously described operation is repeated.

110 After the teeth have been properly jointed or dressed and properly set, in order to insure that the sides of the points of the teeth all lie in the same plane, the device is used as shown in Figs. 7 and 8. In order to accomplish this side dressing, use is again 115 120 125 130

made of a file which is disposed against the side of the body opposite to that from which the plate 23 extends, one flat side of the file being disposed against the heads of the 5 screws 21, and one straight edge of the file being disposed against the central rib 16, whereupon the other edge of the file will be in such position as to be engaged by the beveled edge 36 of the lug 34. Owing to this 10 beveled edge, when the clamping nut 23 is tightened and the clamping member 32 drawn into engagement with the file, the file will be jammed between the lug 34 and the rib 16 and be consequently held firmly as 15 associated with the body. The file also engages upon a screw 40 which is adjustable to place the file in the right position. The operator then grasps the device and positions it as shown in Fig. 7 with the under 20 side of the set block 29 engaging upon the points of the teeth. When the device, together with the file, is then reciprocated, the sides of the teeth will be filed so that they will all lie in the same plane. The 25 provision of the screws 21 is an important feature as by their means it is possible to so adjust the file as to prevent excessive side filing of the teeth. It is obvious that when the screws 21 are screwed out partly, the 30 active flat surface of the file will lie close to the plane of the rib 16 and flange 17 engaging against the side of the saw so that more extensive side filing will be accomplished than when the screws 21 are screwed 35 in. It is believed that this feature will be clear without further explanation.

From the foregoing description and a study of the drawings it will be apparent that I have thus provided a simple and compact device which combines in one implement all the functions of the various separate tools commonly used, and it will also be apparent that the device may be very quickly and easily adapted for use in its 40 various capacities with the minimum expenditure of time and labor and with the maximum result in efficiency.

While I have shown and described the preferred embodiment of my invention, it is 50 of course to be understood that I reserve the right to make such changes in the form, construction, and arrangement of parts as will not depart from the spirit of the invention or the scope of the subjoined claims.

Having thus described my invention, I 55 claim:—

1. A device of the character described comprising a body provided at one edge with overhanging flanges engageable upon the 60 points of the teeth of a saw, said edge being

provided with a recess, a pair of screws threaded into said body within said recess, a plate disposed within said recess and engaging upon the tops of said screws, said plate being provided with holes of less diameter than and registering with said screws whereby access may be had to said screws for adjusting the same, a third screw passing through said plate and into said body between said first named screws for holding 65 said plate in engagement with the heads of said first named screws, said plate projecting beyond one side of said body and having said projecting portion provided with a slot for the passage of a raker tooth of a saw. 70 75

2. A device of the character described comprising a body provided at one edge adjacent one end with a flange, a block on said edge adjacent the other end and having its under surface lying in the same plane with 80 the under surface of said flange, a pair of screws threaded into one side of said body at points spaced from said flange and said block, and a clamping member extending transversely through said block at right angles to said edge and provided at one end with a clamping nut and having its other end provided with a lateral extension terminating in a lug extending toward said body, the edge of said lug toward said block 85 and its opposite edge being beveled, in combination with a file disposable selectively with one flat surface disposed against said screws or with one edge disposed against 90 said body between said screws and said flange 95 and block respectively, said file being engageable by said lug for clamping the file rigidly upon said body.

3. A combination tool of the character described comprising an elongated body having a straight edge provided adjacent said straight edge with a cut out portion, a screw threaded through said body with its point projecting beyond said straight edge and its head disposed within said cut out portion, 100 a central rib extending longitudinally of said body, a flange on said straight edge projecting laterally therefrom the same degree of extension as said rib, a set block secured upon the opposite edge of said body and 105 provided with a beveled anvil surface, the space between said rib and said set block being adapted for the reception of a file disposed selectively flat against said body or flat against the underside of said set block, 110 and clamping means carried by said set block and engaging said file for securing said file rigidly upon said body. 115

In testimony whereof I affix my signature.

WILLARD A. SLOPER.
